PROCESS FOR REFINING ELATERITE

Filed April 15, 1925

Patented Dec. 27, 1927.

1,653,766

UNITED STATES PATENT OFFICE.

ROBERT E. HAUGHEY, OF RAYLE, GEORGIA

PROCESS FOR REFINING ELATERITE.

Application filed April 15, 1925. Serial No. 38,413.

This invention relates to a process for refining elaterite.

The object of the invention is to provide a process and an apparatus for carrying out the process in which the material refined has all gas eliminated therefrom and in which the raw or unrefined material produces its own combustion thereby eliminating the entire expense of fuel.

Another object is to provide an apparatus of this character so constructed that the refined material may be removed directly from the retort should it be desired to so use the material in this manner.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:

Figure 1 represents a vertical section of an apparatus embodying this invention; and

Fig. 2 is a detail sectional view showing the means for directly conducting the refined material from the retort when desired.

There is known on the market a material called "elaterite" which in a manner resembles asphalt and which is very desirable as a pigment for paint and which is mixed in a manner similar to asphalt after it has been refined and reduced to mixing form. The process necessary to reduce this material to liquid form however is very expensive and it is to overcome the expensive process heretofore known that this invention is designed and by means of which this material may be refined and put in liquid form successfully and cheaply.

In the process above referred to which is now employed for refining this material a highly explosive gas is produced during such refining process and which this process entirely eliminates.

The apparatus employed for carrying out this process comprises a retort 1 the side walls 2 of which are preferably constructed of masonry and the bottom 3 in the form of a metal bowl-shaped member having a centrally disposed outlet opening 4 through which the refined liquid material is designed to pass. This retort 1 has an open upper

end 5 and is equipped in one side wall with a door 6 through which the raw or unrefined material is inserted.

Below the retort 1 is a receptacle 7 preferably constructed of masonry and which is equipped with two air tight doors 8 and 9 to afford access to the receptacle for removing refined material.

This pipe 10 is composed of two substantially S-shaped sections 11 and 12 having a swiveled connection as shown at 13 and which is attached to the inner wall of the receptacle 7 preferably by means of a bracket 14 as shown in Fig. 2.

The upper section 11 has its upper end or mouth 15 made larger than the discharge end 16 of section 12 and is designed to be located directly below the outlet 4 in the retort when the refined material is to be discharged directly from the retort to a point outside the receptacle.

An operating device for the section 11 includes a rod 17 which extends through one wall of the receptacle 7 and is equipped at its outer end with a hand grip 18 while at its inner end it is connected with another rod 19 engaged with the section 11 near its upper end and pivotally connected with a bracket 20 mounted on the inner face of the wall of the receptacle 7 as is shown clearly in Fig. 2.

It will thus be seen that by projecting or retracting rod 17 the section 11 will be swung on section 12 to turn the spout 15 either directly under or beyond the outlet 4 of the retort so that the material may be directed into the pipe 10 where it may be discharged into a receptacle containing turpentine or the like vehicle, while the material is in a heated condition or into the receptacle 7 at the will of the user.

In carrying out the process by the apparatus herein shown the unrefined material is placed in the retort 1 through the door 6 and the doors 8 and 9 of the receptacle 7 are closed air tight. After the material has been inserted a spoonful of turpentine is poured on top of the material in the retort and ignited and the refining commences immediately. The raw or unrefined material which as above stated is known as elaterite, sometimes called uterite or mineral rubber, produces its own combustion and thus eliminates the expense of fuel for refining it. Within two hours after the material has been ignited, a tremendous heat is

produced in the retort and the material becomes liquid at the burning point and flows from the outlet opening 4 either into the receptacle 7 or into the mouth of the discharge pipe 10. When this pipe 10 is used the lower end 16 thereof must be submerged in liquid to render it air tight. When it is not desired to conduct the refined material directly from the retort this pipe section 11 is swung laterally away from under the opening 4 and the liquid material flows into the receptacle 7 pouring thereinto in a hot stream. Within fourteen hours from the lighting of the material in the retort the refined material has all been discharged into the receptacle 7 and nothing but dry insoluble matter remains in the retort. The refined material which passes into the receptacle 7 is free from sulphur or other injurious ingredients and the material is then ready to be used as a paint pigment.

From the above description it will be obvious that this process is simple and inexpensive and the apparatus employed for carrying it out is also simple and inexpensive thus eliminating the great objections now advanced against the use of elaterite as a paint pigment.

The retort 1 must have an open top to permit combustion and prevent explosion. This open top retort combined with the air-tight chamber 7 eliminates the explosive gas.

The refined material running into the air-tight chamber 7 becomes hardened in a few hours and can then be broken up with a hammer and be transported in sacks or otherwise to any desired place and by warming will readily combine with the desired paint vehicle so that the paint may be made in quantity.

I claim:

A process of refining elaterite in an open retort supported upon an air-tight container and communicating therewith by means of a restricted opening, comprising placing the crude elaterite in the open retort, igniting the elaterite from the top causing the elaterite to liquefy at the burning point and flow to the bottom of the retort and allowing it to discharge through the restricted opening in the bottom of the retort into the air-tight container.

In testimony that I claim the foregoing as my own, I have hereto affixed my signature.

ROBERT E. HAUGHEY.
